UNITED STATES PATENT OFFICE.

PETER M. WICKSTRUM, OF LINCOLN, NEBRASKA.

INCUBATOR-REGULATOR.

No. 892,635.

Specification of Letters Patent.

Patented July 7, 1908.

Application filed October 17, 1907. Serial No. 397,859.

To all whom it may concern:

Be it known that I, PETER M. WICKSTRUM, a citizen of the United States, residing at Lincoln, in the county of Lancaster and 5 State of Nebraska, have invented a new and useful Incubator-Regulator, of which the following is a specification.

This invention relates to incubators and more particularly to thermostatically operated means for controlling the heating mechanism.

The object of the invention is to provide means of this character capable of minute adjustment, said mechanism being very sensitive to all changes of temperature.

A still further object is to provide mechanism of this character all parts of which can be readily adjusted so as to cause the actuation of the damper at any desired temperature and at any desired speed.

Another object is to provide such an attachment which may be readily applied to an incubator and which is simple and durable as well as efficient.

With these and other objects in view the invention consists of certain novel features of construction and combinations of parts which will be hereinafter more fully described and pointed out in the claims.

In the accompanying drawings is shown the preferred form of the invention.

In said drawings: Figure 1 is a perspective view of the apparatus applied to the incubator, one wall of the incubator being removed.

Fig. 2 is an enlarged view partly in section and partly in elevation of the attachment located within the incubator.

The regulator embodying the present improvements is particularly designed for use in connection with hot air and hot water heaters in which the cap or damper is lowered into closed position when it is desired to raise the temperature of the egg chamber and is lifted from the heater when it is desired to cool the egg chamber by permitting the products of combustion to escape from the heater by a direct path from the lamp. The heater constitutes no part of the present invention but is one of the various forms used in the manner stated. This heater has been designated by the character A in the accompanying drawings.

Secured to one wall of the incubator B is a bracket 1 having an outstanding arm 2 preferably provided with a knife edge 3 having

extensions 4 adjacent each end which constitute abutments or guards.

Loosely mounted on the arm 2 is a looped portion 5 of a rock arm 6 which is preferably formed of strong wire and is provided at one end with a hooked portion 7 while its other end is screw threaded as indicated at 8 so as to be engaged by an adjustable weight 9, the looped portion 5 being located between the ends and having a depending eye 10 disposed between the loop 5 and the weight 9. The damper or cap 11 of the heater is loosely connected to the end 7 of the rock arm.

A rod 12 is pivotally connected to the eye 10 as indicated at 13 and the lower portion of this rod is screw threaded as at 14 and engaged by a nut 15. The rod 14 extends through one end of an operating rod 16 which bears upon the nut 15 and extends through a slot 17 formed within the wall of the incubator B. The inner end of said rod 16 is pivotally connected to an arm 18 extending downward from a bracket 19 which is slidably mounted on a hanger 20 and adjustably connected to it by means of a set screw 21. This hanger is preferably fastened to the top of the incubator in any suitable manner and the extremity of the bracket 19 is engaged by a threaded stem 22 secured to and extending from the center of an annularly corrugated hollow diaphragm 23 formed of material designed to readily expand when subjected to heat. Two of these diaphragms are preferably utilized, the lower one 24 being similar to the upper one and the two being connected at their centers in any preferred manner as by means of solder 25. The lower diaphragm is disposed above the rod 16 and is designed when the diaphragms are extended downwardly under the influence of heat, to contact with and depress the rod 16.

After the parts have been assembled the bracket 19 is adjusted upon the hanger 20 to accommodate thereunder the eggs to be hatched. The diaphragms 23 and 24 are then adjusted by means of stud 22 so that more or less expansion of said diaphragms 23 and 24 can be obtained before the lower diaphragm comes into contact with rod 16. The nut 15 is then adjusted on rod 12 so as to hold the rod 16 normally horizontal. Weight 9 can also be adjusted so as to afford more or less assistance to the diaphragms when raising the cap or damper. After the

parts have been properly adjusted the lamp of the heater can be lighted and the products of combustion will circulate within the heater and soon raise the temperature of the egg chamber. After this temperature within the egg chamber reaches a certain degree the diaphragms 23 and 24 will be expanded downwardly so as to push against the rod 16 and cause it to pull downward on rod 12. Arm 10 6 will therefore be swung upon the knife edge 3 and the cap or damper 11 raised so that the products of combustion can pass directly through the heater without further heating the egg chamber. Thus the temperature 15 within the egg chamber is correspondingly lowered and the parts will return to their initial positions.

It will be seen that by means of the various adjustments provided the apparatus can be 20 positively caused to operate at any predetermined temperature and by employing two hollow diaphragms such as shown the apparatus is rendered very sensitive to changes of temperature.

25 What is claimed is:

1. The combination with a heater, a rock arm, and a damper carried thereby; of a hanger, a bracket slidably mounted thereon, a thermostat adjustably connected to and 30 suspended from the bracket, an oscillating actuating rod pivotally connected to the bracket and extending under and normally out of contact with the thermostat, and an adjustable connection between said rod and 35 the rock arm.

2. The combination with a casing having an aperture therein, a heater, a rock arm, and a damper carried by the rock arm; of a hanger suspended within the casing, a 40 bracket adjustable longitudinally of the hanger and supported thereby, a thermostat

diaphragm adjustably connected to and suspended from the bracket, an actuating rod pivotally connected to the bracket and extending below and spaced from the diaphragm, said rod being movably mounted within the aperture in the casing, and an adjustable connection between the rod and the rock arm. 45

3. The combination with a casing having 50 an aperture therein, a heater, a counterbalanced rock arm, and a damper carried by the arm; of a hanger suspended within the casing, a bracket adjustably mounted upon and supported by the hanger, a thermostat diaphragm, a threaded stem extending from the diaphragm and engaging the bracket, an actuating rod pivotally connected to the bracket and extending under and normally spaced from the diaphragm, said rod being 55 movably mounted within the aperture, and an adjustable connection between the rod and rock arm.

4. The combination with a heater, a rock arm, and a damper carried by the arm; of a 60 hanger, a bracket slidably mounted thereon, a thermostat, a screw threaded stem extending from the thermostat and adjustably engaging the bracket, an actuating rod pivotally connected to the bracket and extending under the thermostat, said thermostat when heated being disposed to move into contact with the rod to shift the same, and an adjustable connection between said rod and the rock arm. 65

In testimony that I claim the foregoing as my own, I have hereto affixed my signature in the presence of two witnesses.
